UNITED STATES PATENT OFFICE.

THOMAS POLLOCK, OF SANTA BARBARA, CALIFORNIA, ASSIGNOR OF ONE-THIRD TO CHARLES O. RIOS, OF SANTA BARBARA, CALIFORNIA.

GOLD-SEPARATOR.

SPECIFICATION forming part of Letters Patent No. 777,803, dated December 20, 1904.

Application filed June 1, 1903. Serial No. 159,644.

To all whom it may concern:

Be it known that I, THOMAS POLLOCK, a citizen of the United States, residing at Santa Barbara, in the county of Santa Barbara and State of California, have invented a new and useful Gold-Separator, of which the following is a specification.

This invention relates to gold-separators.

The object of the invention is to provide an improved apparatus for the separation of fine particles of gold from sand with which the said particles are mixed by forcing the mixture of sand and gold through a body of mercury contained within a suitable receptacle, a stream of water being used to force the mixture of sand and particles of gold through the mercury.

With the object above stated and others in view, which will appear as the invention is more fully disclosed, the same consists, generally stated, in the construction and combination of parts of a gold-separator hereinafter described and claimed, and illustrated in the accompanying drawing, forming a part of this specification, it being understood that changes in the form, proportions, and exact mode of assemblage of the elements therein exhibited may be made without departing from the spirit of the invention or sacrificing any of its advantages.

In the drawing there is shown, partly in elevation and partly in section, a separator constructed in accordance with this invention.

Referring to the drawing, 1 designates a hopper into which the sand containing the particles of gold is introduced. At the bottom of the hopper is located a feed-valve 2, which may be of any preferred form and through which the mixture of sand and fine particles of gold passes downward into the pipe 3. Opening into the pipe 3 a short distance below the hopper 1 is a water-inlet tube 4, disposed downward, as shown, in order to give to the current of water entering the pipe 3 the proper direction. A hose 5 or other suitable conduit is attached to the tube 4, and the water is discharged through it into the pipe 3 with the required velocity, which may

be obtained by gravity or by means of a force-pump, according to circumstances. The pipe 3 is approximately U-shaped, as shown, and at the other end thereof is mounted a mercury-chamber 6, which is preferably of globular form, as shown, and has at one side thereof a glass gage 7, supported in brackets 8, which serves to show the height of the mercury within the chamber. At the top of the gage 7 is provided an inlet-valve 9 in a suitable funnel 10, which forms means for introducing mercury within the chamber as required. In the pipe 3 below the chamber 6 is provided a valve 11, which may be of any preferred form and which serves to prevent the escape of mercury from the chamber before it is needed.

On top of the chamber 6 there is swiveled a discharge-pipe 12, through which the stream of water containing the sand from which the gold has been removed by the amalgamating action of the mercury contained in the chamber passes out from the chamber and is conveyed to any suitable point of deposit.

In the bottom of the bend of the U-shaped pipe 3 is provided a branch pipe 13, closed by a suitable plug 14, which may be secured thereto in any desired manner, as by screw-threads, as shown.

The entire separator is supported in a suitable frame, (designated generally as 15,) and the proper level of the mercury in the chamber prior to starting the separator is indicated by a dotted line at 16.

The operation of the separator is as follows: A suitable quantity of mercury having been introduced into the chamber 6 and the hopper 1 having been charged with gold-bearing sand, the valve 2 at the bottom of the hopper and the valve 11 beneath the mercury-chamber will be opened, allowing the sand and the mercury to pass downward into the U-shaped pipe 3. A current of water of sufficient strength will then be allowed to enter the conduit 5, and the auriferous sand will be forced through the pipe 3 upward through the mercury-chamber 6 and thence out through the escape-pipe 12. As the operation continues

the mercury in the chamber will gradually become charged with the particles of gold contained in the sand which are caught by the mercury in the passage of the sand through the chamber 6, and when it is judged that the mercury has become sufficiently charged with gold the operation of the separator will be stopped by closing the valve 2, cutting off the current of water, and opening the branch pipe 13 at the bottom of tube 2 by removing the plug 14 therefrom, and the mercury charged with gold will be allowed to escape through the branch pipe into any suitable receptacle. The plug 14 will then be replaced, 10 a new supply of mercury will be introduced into the chamber 6, through the charging-valve 9, the valve 11 having previously been closed, and the operation of the separator will be continued in the manner above specified. 15 The amalgam of gold and mercury withdrawn through the branch pipe 13 when cap 14 is removed will be carried to any suitable reduction plant and there treated in the usual way to extract the gold from the amalgam. 20 The excess of space in the globular mercury-chamber 6 over that occupied by the mercury, as indicated by dotted line 16, permits the mercury to settle to the bottom of the chamber and the mixture of water and sand 25 to rise to the top of the mercury in the chamber and become entirely separated from the mercury prior to the passage of the water and sand out through the escape-pipe 12, thus preventing any loss of gold with the outflow of the current bearing the exhausted sand with it. 30 Having thus described the construction and operation of my invention, what I claim as

new, and desire to secure by Letters Patent, is—

1. In a gold-separator, the combination of 40 a **U**-shaped pipe having its arms of different lengths, and disposed vertically, a sand-hopper carried by the longer arm, a valve in the bottom of the hopper, a water-inlet tube beneath and adjacent to the valve and disposed 45 obliquely to the pipe, a normally sealed discharge-outlet arranged in the lowest part of the bend of the pipe, a mercury-chamber carried by the shorter arm of the pipe, a valve in the pipe beneath the chamber, and an outlet-pipe at the top of the chamber. 50

2. In a gold-separator, the combination of 55 a **U**-shaped pipe having its arms of different lengths, and disposed vertically, a sand-hopper carried by the longer arm, a valve in the bottom of the hopper, a water-inlet tube beneath and adjacent to the valve and disposed 60 obliquely to the pipe, a normally sealed discharge-outlet arranged in the lowest part of the bend of the pipe, a mercury-chamber carried by the shorter arm of the pipe, a valve in the pipe beneath the chamber, an outlet-pipe at the top of the chamber, a combined 65 gage and charging pipe connecting with the chamber near its bottom, a funnel carried by the gage, and means for closing the bottom of the funnel.

In testimony that I claim the foregoing as my own I have hereto affixed my signature in the presence of two witnesses.

THOMAS POLLOCK.
